ROTARY DRIVING MECHANISM

Arthur J. Weinig, Golden, Colo., assignor to
 Morse Bros. Machinery Company, Denver, Colo.,
 a corporation of Colorado

Application July 11, 1938, Serial No. 218,621

13 Claims. (Cl. 259—108)

This invention relates to improvements in mechanism for rotary stirring, raking, agitating, conveying or otherwise moving normally loose materials, either dry or wet.

Its field of usefulness includes such devices as thickeners, feeders, roasters, excavators, washers, agitators and the like, and any other machine or operation where divided material is to be acted upon by a rotary element and where resistance to such rotary movement is a variable factor.

As is well known to those skilled in the art, the rotary plows in a thickener, for instance, are subject to variable resistance by the material acted upon, and the mechanism involved may be twisted, damaged or broken if the resistance becomes too great without relief. Furthermore, after a shut-down of operation in such a device, solids may settle around and on the plows and other rotary parts of the mechanism, so that such parts must be raised, dug out or otherwise cleared before again starting. In such operations, a sudden load increase may also result by the addition of a quantity of material into the path of the rotary element.

Therefore, it is an object of this invention to provide a novel mechanism for the purposes set forth that will automatically raise the rotary element to relieve or avoid resistance to its normal forward rotary movement when such resistance builds up to a predetermined degree.

Another object is the provision of such a mechanism that can be selectively raised by power.

A further object is to provide a mechanism of this kind that can be raised with reverse rotation by manual means, when the power is off.

Still another object is to provide, in such a device, means for automatically stopping power input thereto by raising or axial displacement of the rotary element, to a predetermined point.

A still further object is the provision of shearing means for predetermining the degree of resistance to the rotary movement of the rotary element that shall build up before said axial raising or displacement will automatically occur.

Still another object of the invention is to provide means for adjusting the maximum depth to which a rake mechanism or other rotary element will operate.

A still further object is to provide means whereby the rakes will automatically lower and continue to operate as soon as the resistance to their rotary movement is sufficiently reduced.

Other objects and advantages reside in details of design and construction which will be more

fully disclosed in the following description and in the drawings wherein like parts have been similarly designated and in which:

Figure 1 is a side elevation, partly in section, illustrating a thickener built to embody a preferred form of the present invention and in which the novel features of the mechanism have been drawn to a larger scale than other parts, for purposes of clearness and a full understanding of the invention;

Figures 2 and 3 are fragmentary sectional views taken along the lines 2—2 and 3—3 respectively of Figure 1; and

Figure 4 is a fragmentary sectional view illustrating a modified form of the invention.

Referring to the details of the drawings which are herewith included merely as illustrations of typical examples of numerous possible embodiments of the invention, reference character 15 denotes a tank, such as that of a thickener, in which is normally loose or divided material 16, that is being moved toward a central outlet 17 by a rotary element 18 inclusive of plows 19, carried and rotated by an upright shaft 20.

The shaft 20 is journalled for both rotary and axial movement in a steady bearing 21 on an A-frame 22, above the tank, and it is provided with a screw thread 23 having a relatively large or fast lead angle and another screw thread of fine or relatively less lead angle, as at 24. The two threads may be the same or opposite hand.

A rotary drive element, such as a worm gear 25, through which the shaft 20 extends, is in threaded engagement with the fast lead screw 23, and it is journalled on its extended hub, in bearing 26 and is further held against axial displacement by a thrust collar 27 on said hub.

A drive shaft 28 delivers power to drive the mechanism from any suitable prime-mover, such as an electric motor, not shown, through a jaw clutch 29 and a worm 30 in mesh with the worm gear 25 on the shaft 20. A yoke 31 is mounted for conjoint rotation with the gear 25 and clears the shaft at 32. Hand wheels 33 and 34 engage

the fine screw thread 24 of the shaft, the lower wheel 33 being adapted by its hub 33a to thrust against the yoke 31, when desired by the operator.

A shear-pin 35 may be placed in a cross hole 50 in the shaft to rotate therewith and engage against the yoke 31, and normally stationary swivel clamps or collars 36 and 37, are positioned around the shaft 20 to bear against and move vertically along stationary guide-tracks 38 and 39 respectively, when the clamps are tightened

onto the shaft by means of their respective hand set-screws 40 and 41. Each clamp is provided with a radially extending arm 42 and a roller 43 that bears for rolling engagement against and along the respective tracks as illustrated.

The clutch 29 is operable to disconnect the power shaft 28 from the mechanism by means of an arm 44 journalled at 45, and forked at 46 to engage the clutch and at 47 to be engaged and moved upwardly by a set collar 48 on the shaft 20. An electrical circuit breaker may be installed as at 49 to be operated by the upward or axial displacement of the shaft 20, to control or to stop power input to the transmission mechanism described.

Operation

The operation of this example of reduction to practice of the present invention is readily understood. The worm gear 25 transmits driving torque to the shaft 20 but if resistance builds up to a predetermined degree, some or all of the energy will be converted into a lifting force by the fast lead screw 23, on the shaft, so that the plows 19 will pass over the obstacle or will be raised to a point where the resistance to their forward rotary movement is reduced. If the shaft is raised to a point where the collar 48 moves the clutch-arm 44, the power input will be cut off to prevent damage to the mechanism. The electrical circuit-breaker 49 serves a similar function when it is actuated by arm 42a. Both the clutch-arm and the circuit-breaker may be used or either optionally omitted.

All parts of the transmission mechanism are accessible to an operator in actual practice, by walks and platforms not shown because they would obscure some of the important features of the machine. When an operator optionally desires to raise the rotary element under power, he may do so by tightening the hand set screw in either clamp collar 36 or 37 which will convert the power energy input from rotary movement to lifting force.

This means of power lifting is designed to greatly reduce the manual labor involved when an operator is required to lift a plurality of thickener rakes in a plant prior to a shut-down for abbreviated weekly operations or for any other causes. Thickeners built according to the present invention may be cared for by the usual operators who merely walk along a platform, not shown in the drawings, from one thickener to the next. The operators only have to tighten swivel clamp 37 by means of its hand set screw 41 on each thickener mechanism, whereupon the rotary elements will be automatically raised to shut off the power or disengage the clutches. During the period of the shut-down, the respective mechanisms will be held in their elevated positions since they are held from rotation with reference to their respective drive mechanisms by the tightened clamps.

Upon starting of the operations again, the attendant has only to release the hand set screws 41 and their associated clamps 37, whereupon the mechanisms then rotate downwardly into their operating positions, and their clutches and/or controlling circuit breakers are put into operative positions quickly and automatically. It will readily be seen that these features of the present invention are highly important in reducing the manual labor of the usual operators in the operation of any device or any battery of devices built according to this disclosure.

Other modes of selectively elevating the rotary mechanism are as follows; the two hand wheels 33 and 34, can be locked together and held manually to effect the same result. Or the hand wheels can be locked and the shaft manually rotated differentially from the rotation of the gear 25. Obviously, any relative rotation between the gear 25 and the shaft 20 will effect longitudinal or axial movement or displacement of the shaft since the gear is held against such movement.

The shaft 20 can also be raised manually by using the hand wheel 33 as a thrust nut against the top of yoke 31, either with or without the gear turning under power. When the power is off and the hand wheel is thus used, the shaft and its rotary mechanism will be raised and rotated reversely to its normal forward movement, which is an excellent method of freeing the plows from a settled superposed load of material. Any lifting of the shaft by any manual means while the gear 25 remains stationary, will rotate the shaft and its associated mechanism reversely because of the screw-thread 23. The threads 23 and 24 are preferably of opposite hand to facilitate some of the functions of the hand wheels above set forth.

A shear pin 35 may be inserted at the option of the operator, in a cross hole in the shaft as illustrated, to increase, to a predetermined degree, the resistance to the rotary movement of the shaft that will be required before the mechanism will begin to raise. When the shaft is sufficiently resisted in its forward rotation to shear the pin, lifting will begin because relative rotary movement between the gear and the shaft is possible. In the drawings, Figure 1, the pin 35 is shown positioned in the shaft for purposes of illustration. During use, a relatively small increase in resistance by material 16, to rotation of the driven rotary element, will slow and raise the latter and bring the yoke to bear in driving relation against the pin to impart greater torque to the shaft 20, until the pin fails. Thus the improved mechanism that is the subject of the present invention, is under both automatic and manual control to effect the objectives set forth.

Figure 4 illustrates an embodiment of a modified form of the invention and is merely illustrative of another typical use for which it is well adapted. In this embodiment which is a drive for the rabbles of an ore roaster, reference character 60 denotes a hearth, 61 the rotary rabbles that are carried on and rotated by a hollow air-conducting driven shaft 62, that is journalled at 63 for both axial and rotary movement.

The driving or power transmission mechanism comprises a power shaft 64, journalled on supporting frame 65, at 66. A bevel pinion 67, on shaft 64, drives bevel gear 68 to rotate shaft 69 journalled on a thrust bearing 70 on foundation 71, and in a steady bearing 70a.

The shaft 69 has a fine screw thread 72, an annular recess 73, and an upper end portion 69a, that has a coarse or fast lead screw thread 74 that engages in the lower portion of driven rabbles shaft 62 as shown. Shaft 69 is hollow as at 69b. A hand wheel 75 engages the said fine thread 72 to thrust against and lock a similarly threaded capstan collar 76 on the shaft 69, when desired. An upper capstan collar 77 is keyed to the driven rabbles shaft 62 by key 77a held by set screw 78. Washers 79 and 80 provide a bearing for the upper capstan on the lower one, and shear pins 81 connect the two for the transmission of limited

driving torque. Both capstans are provided with a plurality of radial holes 82 into which a bar or the like may be manually inserted to rotate them or to resist rotation thereof as desired.

The lower capstan has a swivel ring clamp 83, that has a hand set screw 84 that is provided with a roller 85 which bears against the frame at 65a. The upper capstan has a similar clamp ring 86, set screw 87 and roller 88 that rolls vertically between frame parts at 65b. The capstan 71 is provided with an inwardly projecting annular flange 89 that projects into the annular recess 73 of the drive shaft 69. The preferred screw thread angle or lead angle for the fast lead screw threads, in all forms of the invention, is tangent function equals 1 over 3.1416 or a lead of one diameter per turn. This angle may be varied to suit conditions.

The operation of the roaster drive is generic to the thickener drive and is obvious. Resistance to rotation of shaft 62, either from material being moved on the hearth, or mechanical or manual resistance, will raise the rabble assembly carried on said shaft 62. Shear pins 81 function as hereinabove set forth, and are optionally used. The lower capstan collar 83 and hand wheel 75 are used to raise the rotary driven assembly for a semi-permanent setting, or downward limit, while the inwardly projecting flange 89 of the upper capstan 71 limits the upward axial movement of driven shaft 62 with its rotated members.

The stopping of rotation of the lower capstan 83 by any of the disclosed means while the shaft 69 is rotated will lift the entire assembly to a minimum elevation at which it may be set by locking with the hand wheel 75. Likewise, the same result may be effected by turning the capstan 76 while the power drive is stopped.

The upper capstan 71, the driven shaft 62 and the rabbles 61, function as an integral unit and are under both automatic and optional selective control as to elevation within the limits above set forth to accomplish the desired objectives. Holding the capstan 71 from rotation by manual means or by the ring clamp 86 will convert rotary power motion into lifting or axial motion. Likewise, lifting the rotated assembly by any means for any purpose, while the power drive is stopped, will rotate the rabbles in a direction that is the reverse from normal. Air for the roaster is taken in through air hood 90 at 91. The capstans, ring clamps and other annular members may be made "split" or in halves to facilitate assembly.

These examples illustrate the advantages gained and the wide field of practical utility of this invention, and its many applications to industry.

While this specification discloses preferred means for reducing the present invention to practice and a preferred embodiment of the invention, changes may occur to those skilled in the art and may be made within the scope of the appended claims, without departing from the spirit of the invention.

What I claim and desire to secure by Letters Patent is:

1. The combination with a rotary element of the character described, of a power transmission mechanism therefor comprising a rotary drive-and-lifting member, a rotary driven element in concentric threaded engagement therewith journaled for both rotary and axial movement, and means for optionally resisting the rotary movement of the driven element effecting relative ro-

tary movement between the drive-and-lifting member and the driven element whereby the latter is moved axially by said member.

2. The combination with a thickener tank or the like of a rotary stirring element of the character described, and a power transmission mechanism therefor comprising a rotary drive-and-lifting member, a rotary driven element in concentric threaded engagement therewith journaled for both rotary and axial movement, and a normally stationary clamp on the driven element for resisting the rotary movement of the driven element effecting relative rotary movement between the drive-and-lifting member and the driven element whereby the latter is moved axially.

3. The combination with a thickener tank or the like of a rotary stirring element of the character described, and a power transmission mechanism therefor comprising a rotary drive-and-lifting member, a rotary driven element in concentric threaded engagement therewith journaled for both rotary and axial movement by said member, a normally stationary clamp on the driven element for selectively resisting the rotary movement of said driven element to axially move the same, and a stationary guide-track for the clamp.

4. The combination with a thickener tank or the like of a rotary stirring element of the character described, and a power transmission mechanism therefor comprising a rotary drive-and-lifting member, a rotary driven element in concentric threaded engagement therewith journaled for both rotary and axial movement by said member, a normally stationary clamp on the driven element for selectively resisting the rotary movement of said driven element to axially move the same, a stationary guide-track for the clamp, and a roller on the clamp adapted to follow along said guide-track during said axial movement.

5. The combination with a rotary element of the character described, of a power transmission mechanism therefor comprising a rotary drive-and-lifting member, a rotary driven element in concentric threaded engagement therewith, adapted for axial displacement thereby when its rotary movement is resisted to a predetermined degree, and means mechanically to resist the rotary movement of the driven element.

6. The combination with a rotary element of the character described, of a power transmission mechanism therefor comprising a threaded rotary drive-member, a rotary driven element in concentric threaded engagement therewith, adapted for axial displacement when its rotary movement is resisted to a predetermined degree, and means manually to effect axial displacement with reverse rotation of the driven element when said power drive-member is stopped.

7. A thickener comprising a tank, material-moving rakes therein, a threaded axially movable shaft supporting the rakes for rotary and elevating movement, a shaft-driving-and-lifting member in threaded engagement with the shaft, for normally rotating the same and adapted to elevate the shaft and the rakes when the material being acted upon by the latter resists their normal rotary movement to a predetermined degree, and means for selectively resisting said rotary movement to divert driving force of the member into lifting force.

8. A thickener comprising a tank, material-moving rakes therein, a threaded axially movable shaft supporting the rakes for rotary and

elevating movement, a shaft-driving-and-lifting member in threaded engagement with the shaft, for normally rotating the same and adapted to elevate the shaft and the rakes when the material being acted upon by the latter resists their normal rotary movement to a predetermined degree, and a shear-pin connecting the member with the shaft for resisting relative movement therebetween to a predetermined degree.

9. A thickener comprising a tank, material-moving rakes therein, a threaded axially movable shaft supporting the rakes for rotary and elevating movement, a shaft-driving-and-lifting member in threaded engagement with the shaft, for normally rotating the same and adapted to 10 elevate the shaft and the rakes when the material being acted upon by the latter resists their normal rotary movement to a predetermined degree, and a clamp for selectively resisting said rotary movement to divert driving force of the 15 member into lifting force.

10. Power transmission mechanism for a thickener or the like, comprising a threaded rotary drive member, a substantially vertical rotary driven element concentrically positioned through 20 said drive member in threaded association therewith and journaled for both rotary and axial movement, and a shear pin connecting the drive member with the driven element.

11. Power transmission mechanism for a 30 thickener or the like, comprising a threaded rotary drive member, a substantially vertical ro-

5 tary driven element concentrically positioned through said drive member and having a thread of relatively large lead angle in engagement with the drive member and another thread of relatively less lead angle and journaled for both rotary movement and axial movement, means selectively to resist rotary movement of the driven element, and a manually operable axial thrust member in engagement with the thread having the lesser lead angle.

12. In a device of the character disclosed, the improvement which comprises a power driven rotary stirring element journaled for both rotary and axial movement, and means manually to effect axial displacement of said element with rotation thereof in a direction reverse to that of its normal power driven direction of rotation.

13. Power transmission mechanism for a thickener or the like, comprising a threaded rotary drive member, a rotary driven element concentrically positioned through said drive member and having a thread of relatively large lead angle in engagement with the drive member and another thread of relatively less lead angle and journaled for both rotary movement and axial movement, means selectively to resist rotary movement of the driven element, and a manually operable axial thrust member in engagement with the thread having the lesser lead angle.

ARTHUR J. WEINIG.
